SAFETY DEVICE FOR GAS APPLIANCES

Sebastian Karrer, Washington, D. C., and Paul L. Betz, Baltimore, Md., assignors to Consolidated Gas Electric Light and Power Company of Baltimore, Baltimore, Md., a corporation of Maryland

Application July 7, 1939, Serial No. 283,308

14 Claims. (Cl. 137—153)

This invention relates to safety devices for gas appliances, and more particularly to means which will operate automatically to prevent flow of gas to the appliance or appliances if an effort is made to initiate such flow while a gas valve or other outlet is open. The invention has particular utility in conjunction with prepayment gas meters, but as will be apparent to those skilled in the art and as hereinafter pointed out, the invention may be applied to perform like functions in other combinations involving gas appliances.

In prepayment gas meters a valve is ordinarily provided inside the meter case for operation by a coin-controlled device so that, upon deposit of one or more coins, the valve is opened and will remain open until a predetermined quantity of gas has passed through the meter. When this quantity has been used up the valve closes, and if any burner is in operation at that time the flame is extinguished although the appliance cock is open. If another coin is then inserted without previously closing the appliance cock unignited gas will escape and may be productive of fire, explosion, gas poisoning or other dangerous conditions.

It is an object of this invention to provide a means for eliminating the aforesaid hazard in the use of prepayment gas meters.

A similar situation may arise when it is necessary to cut off the gas supply at a main. Unless all burners are shut off individually in the affected appliance or area, restoration of gas flow will result in gas escape from any burner which was ignited at the time the gas supply was discontinued. Thus if the supply main to a house is shut off it is necessary to make certain that all burner cocks, as for example those on hot water heaters, be shut off before the gas supply is restored if a hazardous condition is to be avoided.

It is an object of this invention to provide a safety device which may be associated with an individual gas appliance or with a plurality of gas appliances in a given area to eliminate the necessity of first visiting all the burners and making sure that they are shut off before the gas supply is restored.

A further object of this invention is to provide prepayment gas meters with means which may be readily incorporated in or associated with such meters for preventing flow of gas following an interruption of the gas supply unless all of the burners are turned off.

Another object of this invention is to provide means which may be applied to a gas supply

conduit, whether that supplying an individual appliance or that supplying a plurality of appliances over a smaller or larger area, which will prevent unsafe conditions arising from interrupting the gas supply without first requiring that all burners be visited to make sure that they have been shut off.

Another object of this invention is to provide a device of the type characterized which is simple in construction, compact, inexpensive to manufacture and install, and highly efficient in operation.

Other objects of this invention will appear as the description thereof proceeds.

The invention is capable of receiving a variety of mechanical expressions, several of which are shown on the accompanying drawing, but it is to be expressly understood that the drawing is for purposes of illustration only and is not to be construed as a definition of the limits of the invention, reference being had to the appended claims for that purpose.

Referring in detail to the accompanying drawing, wherein the same reference characters are employed to designate corresponding parts in the several figures—

Fig. 1 is a somewhat schematic axial section showing a valve arrangement embodying the present invention and adapted to be incorporated in a prepayment gas meter;

Fig. 2 is an enlarged view of the valve operating means of Fig. 1;

Fig. 3 is a somewhat schematic axial section showing another embodiment of the invention adapted to be applied to a prepayment gas meter but employing a diaphragm means for assisting both the valve closing and valve opening forces of the device; and

Fig. 4 is a somewhat schematic axial section showing another embodiment of the invention which may be connected in the gas line ahead of a particular appliance to be protected or which may be associated with a gas main controlling the gas supply to a plurality of appliances over a smaller or larger area.

Referring first to the embodiment of Figs. 1 and 2, which shows a structure that may be readily incorporated in the interior of a prepayment gas meter, 10 designates a chamber which may be formed in the gas meter in any suitable way, the meter and its coin controlled mechanism being not illustrated as the same constitute no part of the present invention except as herein indicated. Gas may enter the chamber 10 from the main or supply line through inlet 11 and

leave the chamber 10 through outlet 12 on its way to the appliance or appliances controlled by said meter.

Formed within the chamber 10 in any suitable way is a valve seat 13 with which cooperates a valve member 14 of any suitable form. As illustrated, a metal to metal contact is provided between the valve member 14 and its seat 13, although any other suitable type or character of valve may be employed, as a valve disk of deformable material or a valve disk carrying an annulus of yieldable material for cooperation with the valve seat. As illustrated, see particularly Fig. 2, valve member 14 carries a plug 15 suitably attached thereto as by threading and having a spring centering extension 16 projecting downwardly therefrom as viewed in Figs. 1 and 2. If preferred, however, member 15 or its equivalent may be formed integrally with the valve disk 14. Member 15 is provided with an aperture 17 through which extends a stem 18 that has formed on or attached to its inner or lower end as viewed in Figs. 1 and 2 a suitable flanged or dished plate 19 between which and the valve member 14 is disposed a coil spring 20. The bore of aperture 19 is somewhat larger than the cross section of the stem 18 so as to provide a surrounding annular bleeder passage through which gas may flow from the region above the disk 14, as viewed in Figs. 1 and 2, and through said annular space 21 to the chamber 22 below said valve disk.

Formed on or suitably attached to the opposite end of valve stem 18 is a second valve member 23 adapted to cooperate with a valve seat 24 surrounding the upper end of the aperture 17, as viewed in Fig. 2, and here shown as formed on the plug 15, so that when valve member 23 engages seat 24 flow of gas through the bleeder passage 21 is prevented. As illustrated, a metal to metal contact is also provided at this last named valve, but as in the case of valve member 14, any other suitable construction of valve member may be used, as by providing the disk 23 with a deformable disk or annulus for engagement with the seat 24. Attached to valve disk 23 is a yoke 25 to which is pivoted a lever 26 that is suitably mounted as by the pivot 27 and that is actuated by the coin controlled mechanism of the gas meter.

As shown in Fig. 1, both valves are closed by the engagement of disk 14 with its seat 13 and by the engagement of disk 23 with its seat 24, and lever 26 as shown in full lines is in that position which it assumes after the predetermined quantity of gas has passed the meter so that gas flow is discontinued until an additional coin or coins are deposited in the coin collecting device thereof. Upon inserting a coin in the coin collecting device, arm 26 is moved from its full line to its dotted line position as shown in Fig. 1. As yoke 25 is pivotally attached to lever 26 disk 23 is lifted with respect to its seat 24, as shown in Fig. 2, and against the tension of the spring 20, the additional tension thus arising from the compression of the spring 20 tending to also lift valve member 14 away from its seat 13. If all burners controlled by the device under discussion are closed gas may flow through the bleed opening provided by the annular passage 21 until it builds up such a pressure at the underside of the disk 14 that, together with the compression of spring 20, the disk 14 will be raised away from its seat 13 and gas may flow to the appliance or appliances controlled by the meter.

Assume, however, that at the time the meter valve was closed a burner was in operation and

the gas cock thereof has not since been closed: Atmospheric pressure will now exist in the chamber 22 due to the open gas cock, and the pressure of the gas on the upper face of the valve disk 14 is more than sufficient to overcome the additional tension of the lever 26, spring 20 being suitably designed so that the tension imposed thereby on the valve disk 14 is less than the difference of pressure existing above and below the valve disk 14 when any gas cock communicating with the outlet 12 is open. Thus the valve 14 will remain on its seat 13 due to the difference in pressures above and below the valve disk 14 and only such gas can escape as will flow through the bleeder passage 21—which may be sufficient to constitute a warning that gas is escaping but not sufficient to produce a dangerous condition.

As soon as all burners communicating with the outlet 12 are closed, however, the escape of gas through the bleeder opening 21 will result in a gradual increase in pressure in the chamber 22 until a pressure is reached such that the tension of spring 20 will overbalance the seating force theretofore exerted on valve member 14 by said pressure difference, whereupon spring 20 will raise valve member 14 and permit normal flow of gas through the outlet 12. It is preferred that when valve disk 14 is open seat 24 reengages disk 23 so that valve member 14 will not vibrate when in its open position. When the predetermined quantity of gas has again been used up valve member 14 which has been lowered toward its seat as rapidly as permitted by the movement of the arm 26, reaches a position wherein it will by snap action reengage its seat 13 owing to the pressure changes arising from the decreasing port opening.

In the embodiment of Fig. 2 the force for holding the valve member in contact with its seat is only the difference in pressure on the two sides of the valve member 14 as modified by the action of the spring 20. Fig. 3 shows an embodiment which may also be incorporated in a prepayment gas meter and which is provided with a diaphragm or other analogous means to assist in holding the valve closed when an unsafe condition exists and to help unseat the valve when proper conditions are established. The embodiment of Fig. 3 employs a chamber 10, inlet 11, outlet 12, valve seat 13, valve member 14, stem 18, spring seat 19, spring 20, bleeder passage 21, auxiliary valve disk 23, yoke 25 and lever 26 as in the embodiments of Figs. 1 and 2, these and associated parts being shown as of the same construction and therefore further detailed description thereof is unnecessary.

In the embodiment of Fig. 3, auxiliary chamber 30 is provided in association with the chamber 10 in any suitable way, being shown as defined by an annular wall 31 suitably attached to or integral with the wall of chamber 10. Suitably mounted on the annular wall 31 so as to form a gas-tight seal therewith is a diaphragm 32 of any suitable size and material, the same being shown as clamped to the edge of said wall 31 by a plate 33 and screws 34. Attached to the center of said diaphragm is a stem 35, said stem being shown as having a head 36 and extending through a pair of washers 37 and 38 between which the central portion of the diaphragm is compressed by a nut 39 mounted on a threaded portion of the stem 35. Washer 38 is shown as of inverted cup-shaped or dished formation, and interposed between the same and the wall 40 of

the chamber 10 is a coil spring 41 of suitable tension to perform the function hereinafter described. Spring 41 may be centered or held in its proper location by a lug 42 formed on or attached to the wall 40. Stem 35 extends through an aperture 43 in the plate 33 which preferably makes only a relatively small clearance with said stem for a reason to be referred to, and the opposite end of said stem is preferably guided, so as to enforce rectilinear movement, by reception in the recess 44 of a lug 45 suitably attached to or formed on the cover plate 46 of the chamber 10.

Secured to the stem 35 at spaced points along its length suitably selected to perform the functions next to be described are disks, pins or other suitable actuating elements 47, 48 and 49. Pivotally mounted at 50 and 51 on the wall of the chamber 10 in any suitable way are levers 52 and 53 shown as apertured for passage of the stem 35, lever 52 being operatively related to member 47 and lever 53 extending between the operating members 48 and 49. Lever 52 is disposed below the valve disk 14 as viewed in Fig. 3, and lever 53 is disposed above said valve disk, and as shown said levers have bent ends 54 and 55 for engagement with and actuation of the valve disk. In the relationship of the parts shown in Fig. 3, lever 53 is exerting a force on the valve member 14 and tending to maintain it in seated position, while lever 52 is out of contact with said valve disk 14. Chamber 30 is connected with chamber 22 beneath the valve disk 14, as viewed in Fig. 3, by a bleeder passage 56 formed in any suitable way and thereby providing for the establishment in the chamber 30 of the same pressure as exists in the chamber 22.

Assume that the amount of gas predetermined by a previously deposited coin has already passed through the meter, so that lever 26 has been moved to the full line position shown in Fig. 3, whereby valve members 14 and 23 are both in closed position as shown and as explained in conjunction with the embodiments of Figs. 1 and 2. If a new coin is now deposited in the meter, lever 26 will move from the solid line to the dotted line position, raising valve member 23 from its seat 24 and, as in the embodiment of Figs. 1 and 2, compressing spring 20 to impose an initial opening tension on the valve member 14, although if preferred the opening and closing of the valve member may be dependent only on the pressure differential exerted on the diaphragm 32. If a burner has been left open at the time the flow of gas was discontinued, however, there will be atmospheric pressure in the chamber 22, as in the embodiments of Figs. 1 and 2, and the tension of the spring 20 owing to the appropriate design of said spring 20, is insufficient to overcome the difference in pressure existing on the two sides of the valve member 14.

In this embodiment atmospheric pressure also exists in the chamber 30 because of the bleeder opening 56, while gas pressure is acting in chamber 10 on the upper face of the diaphragm 32, as viewed in Fig. 3, so that said diaphragm is depressed against the tension of the spring 41, and stem 35 engages member 49 with lever 53 which in turn engages the face of the valve member 14 to hold said valve member closed. Lifting of the valve member 23 permits a small leakage of gas through the bleeder passage 21, as in the embodiments of Figs. 1 and 2, but as long as the gas burner remains open, the pres-

sure cannot change in chambers 22 and 30 to alter the condition just described.

When all of the burners communicating with the outlet 12 are closed, however, the leakage of gas through the annular bleeder passage 21 results in pressure being built up in both chambers 22 and 30. This decrease in the difference in pressure on the two sides of the valve member 14 not only enables spring 20 to move valve member 14, but the decrease in the pressure differential on the two sides of the diaphragm 32 results in coil spring 41 moving valve stem 35 upwardly and thereby first removing member 49 from lever 53 to release the lever 53 and then 15 engaging member 48 with said lever 53 to positively move said lever upwardly out of the way of the valve member 14, while member 47 simultaneously moves lever 52 to engage valve member 14 and assist the latter in its opening movement. Hence in this embodiment as just described the valve member 14 is opened by the combined action of the springs 20 and 41 when the pressure difference on the two sides of the valve member 14 and the diaphragm 32 has been decreased by gas flow through the bleeder passages 21 and 56.

When a predetermined quantity of gas has passed lever 26 will again move from dotted to full line position, and the actuating force on said lever 26 is sufficient to move the valve member 14 to its closed position even though lever 52 be in contact therewith, spring 41 being thereby tensioned to assist in the next opening movement of the valve member 14 if lever 26 is moved from full line to dotted line position while all burners are closed so that gas pressure rather than atmospheric pressure exists in the chambers 22 and 30. But if atmospheric pressure exists in chambers 22 and 30 the parts are moved to the position shown in Fig. 3 and valve member 14 is held closed until all gas valves or other outlets are closed.

Should diaphragm 32 rupture for any reason full flow of gas to the burners would not follow, as only such gas could escape as can flow through the bleeder opening 56, and even this flow can be further reduced by making the clearance at 43 heretofore referred to of less cross sectional area than the passage 56.

50 The embodiments of Fig. 4 is more particularly adapted for incorporation in a supply conduit either just ahead of a gas appliance or in a main for controlling a number of appliances although, as will be apparent, the construction now to be described could also by suitable adaptation be incorporated within a prepayment gas meter analogously as the embodiments heretofore described could by suitable adaptation be employed outside of the gas meter either ahead of an individual 55 appliance or in a main leading to a plurality of appliances. In this embodiment the casing 60 has an inlet 61 and an outlet 62, and interiorly the same is provided in any suitable way with a valve seat 63. Cooperating with said valve seat 65 is a valve member 64 of any suitable form and construction, such as heretofore referred to, and mounted on a diaphragm 65, as by a screw 66. Diaphragm 65 is mounted in any suitable way, as by clamping its periphery between the flanges 67 and 68 of the casing 60 and cover member 69 by means of screws 70. The central portion of the diaphragm as illustrated is compressed between the valve member 64 and a cup-shaped or dished washer 71 by the screw 66, and interposed between said washer 71 and an adjustable plug 72

threadedly mounted in an aperture 73 suitably formed on the cover 69 is a coil spring 14. By adjusting the position of the plug 72 the tension of said spring 14 can be adjusted to provide for opening of the valve member upon the occurrence of that difference in pressure on said diaphragm that is desired. Valve member 64 is shown as provided with a bleeder opening 75 as a means of communication between the chamber 16 below the valve member 64, as viewed in Fig. 4, and the chamber 11 beneath the diaphragm 65 and with which the outlet 62 communicates. Chamber 18 above the diaphragm is maintained at atmospheric pressure by any suitable vent, here shown as provided by an aperture 79 in the plug 72.

Assume that the inlet 61 is in communication with any suitable main and that the outlet 62 is in communication with any suitable meter or meters or other appliance or appliances. As long as gas pressure exists in chamber 11 diaphragm 65 is flexed upwardly, as viewed in Fig. 4, against the tension of the spring 14, by the difference in pressure acting on the two sides of said diaphragm. If for any reason the gas pressure is cut off at the inlet 61 and any burner is in operation at that time, atmospheric pressure is communicated to chamber 11 and spring 14 causes the member 65 to flex downwardly as viewed in Fig. 4 and engage valve member 64 with said seat 63. When the gas pressure is restored at the inlet 61, still assuming there is an open outlet or burner in communication with 62, atmospheric pressure will continue to exist in the chamber 11 and spring 14 will hold valve member 64 closed as long as such pressure condition exists. As soon as all outlets are closed, however, gas pressure bleeding through the passage 75 into chamber 11 will re-establish excess pressure on the underside of said diaphragm 65 as viewed in Fig. 4 and open the valve member 64 against the tension of the spring 14, again permitting full flow of gas through the outlet 62. If all of the outlets communicating with 62 are closed when the gas pressure is cut off at 61, and remain closed, the diaphragm 65 will be automatically flexed upwardly again, against the tension of the spring 14, as soon as gas pressure is restored at 61.

If for any reason diaphragm 65 should rupture gas can escape only as permitted by the relatively small bleeder opening 75 and therefore no full flow of gas is permitted.

It will therefore be perceived that in all of the embodiments disclosed a device has been provided which is entirely automatic in operation and which is effective to stop the gas flow, except for such small leakage as can occur through the bleeder opening, if when gas flow is restored after a discontinuance any burner or other outlet in communication with the device happens to be open, and only upon the closure of all burners or outlets can gas flow be reestablished. No manually operable means are involved in the device and therefore it is impossible by manual resetting of any element, through carelessness or otherwise, to reestablish gas flow as long as any gas valve in the line on the outlet side of the device remains open. Devices have heretofore been proposed whereby a predetermined drop of pressure in the gas main has resulted in a valve being closed, said valve being manually resettable and contemplating that an authorized person will reset the valve when proper gas pressure has been reestablished. But devices of this character are not suitable for prepayment gas meters for example, because of the danger that the house-

holder may deposit a coin or manually reset the valve without taking proper precautions to assure that all gas valves have previously been closed. The present invention obviates the dangerous conditions that may arise from depositing a coin in a prepayment gas meter or otherwise restoring gas pressure without first making certain that all gas valves are closed, as gas cannot flow to the burners as long as any burner or other outlet in communication with the safety device is open—and this cannot be changed by any operation of a manually manipulated element.

While the embodiments of the invention illustrated on the drawings have been described with considerable particularity, it is to be expressly understood that the invention is not restricted thereto, as the same is capable of receiving a variety of mechanical expressions, as will now be apparent to those skilled in the art, while changes may be made in the details of construction, arrangement and proportion of parts, bellows or other comparable elements may be used in the place of diaphragms, any suitable construction of valves may be employed, etc., and certain features may be used without other features, without departing from the spirit of this invention. Reference is therefore to be had to the appended claims for a definition of said invention.

What is claimed is:

1. In a safety device for gas appliances, in combination with means providing inlet and outlet chambers and a valve between said chambers for controlling the flow of gas therebetween, means operable from the exterior of said device to condition the same for opening said valve and means for automatically rendering said valve opening means incapable of opening said valve if any outlet in communication with said outlet chamber is open, said means including a bleeder passage between said inlet and outlet chambers and means inoperable from the exterior of said device and associated with said valve and effective to open the valve only when gas pressure develops in said outlet chamber, by gas flow through said bleeder opening, when all outlets are closed.

2. In a safety device for gas appliances, in combination with means providing inlet and outlet chambers and a valve member cooperating with a valve seat to prevent flow of gas between said chambers, means for automatically assuring that said valve member shall remain in closed position if any outlet in communication with said outlet chamber is open when gas pressure is admitted to said inlet chamber, said means including a bleeder passage between said inlet and outlet chambers, resilient means operable from the exterior of said device to bias said valve member toward open position, and automatic means inoperable from the exterior of said device for opening said valve member when gas pressure develops in said outlet chamber by reason of gas flow through said bleeder passage when all outlets are closed and for preventing opening of said valve member when gas pressure cannot develop in said outlet chamber by reason of an open outlet connection.

3. In a safety device for gas appliances, in combination with means providing inlet and outlet chambers and a valve member cooperating with a valve seat for controlling the flow of gas between said chambers, means automatically operative to assure that after closure said valve member remains closed as long as said outlet chamber is below a predetermined pressure, said

means including a bleeder passage between said inlet and said outlet chambers, said valve member being subjected on its opposite sides respectively to the pressures in said inlet and said outlet chambers, and resilient means cooperating with said valve member for biasing said valve member toward open position but operable to effect opening of said valve member only when a predetermined pressure is established in said outlet chamber, if, by reason of gas flow through said bleeder passage, all of the outlets communicating with said outlet chamber are closed.

4. In a safety device for gas appliances, in combination with means providing inlet and outlet chambers and a valve member cooperating with a valve seat for controlling the flow of gas between said chambers, means automatically operative to assure that said valve member remains closed as long as said outlet chamber is below a predetermined pressure, said means including a bleeder passage between said inlet and outlet chambers, diaphragm means subjected at its opposite sides respectively to the pressures in said inlet and said outlet chambers and cooperating with said valve member and actuated by a difference in pressure on the opposite sides thereof, and resilient means cooperating with said diaphragm means for biasing said valve member toward open position, said diaphragm means being effective to cause opening of said valve member only when gas pressure has developed in said outlet chamber, by reason of gas flow through said bleeder passage, if all outlets in communication with said outlet chamber are closed.

5. In a safety device for gas appliances, in combination with means providing inlet and outlet chambers and a valve member cooperating with a valve seat for controlling the flow of gas between said chambers, means automatically operative to assure that said valve member remains closed as long as said outlet chamber is below a predetermined pressure, said means including a bleeder passage between said inlet and outlet chambers, a diaphragm subjected to the pressure in said inlet and said outlet chambers, valve operating members operatively connecting said valve member with said diaphragm, resilient means cooperating with said diaphragm to bias said diaphragm toward open position of said valve, and resilient means for biasing said valve member toward open position but automatically operable to open said valve member only when gas pressure, by reason of gas flow through said bleeder passage, develops in said outlet chamber.

6. In a safety device for gas appliances, in combination with means providing inlet and outlet chambers and a valve member cooperating with a valve seat for controlling the flow of gas between said chambers, means automatically operative to assure that after closure said valve member remains closed as long as any outlet in communication with said outlet chamber is open, said means including a bleeder passage between said inlet and outlet chambers, a valve stem on which said valve member is movable, a spring reacting between said valve member and said valve stem, and means for compressing said spring to bias said valve member toward open position, the effect of said spring being insufficient to overcome the difference in pressure on the two sides of said valve member unless gas pressure has developed in said outlet chamber, by reason of gas flow through said bleeder passage, as a result of all outlets communicating

with said outlet chamber being closed and said spring when biased being operative to open said valve member when said gas pressure has developed in said outlet chamber.

5 7. In a safety device for gas appliances, in combination with means providing inlet and outlet chambers and a valve member cooperating with a valve seat for controlling the flow of gas between said chambers, means automatically operative to assure that after closure said valve member remains closed as long as any outlet in communication with said outlet chamber is open, said means including a bleeder passage between said inlet and outlet chambers, a diaphragm subjected at its opposite sides respectively to the pressure in said inlet and outlet chambers and operable to move said valve member, and a spring cooperating with said diaphragm, said diaphragm and spring being effective to open said valve member only if the gas pressure in said outlet chamber, by reason of gas flow through said bleeder passage, is above atmospheric pressure as a result of all outlets in communication with said outlet chamber being closed.

15 8. In a safety device for gas appliances, in combination with means providing inlet and outlet chambers and a valve member cooperating with a valve seat for controlling the flow of gas between said chambers, means automatically operative to assure that after closure said valve member remains closed as long as any outlet in communication with said outlet chamber is open, said means being inoperable from the exterior 30 of said device and including a bleeder passage between said inlet and outlet chambers, a diaphragm cooperating with said valve member and subjected on its opposite sides respectively to the pressure in said inlet and said outlet chambers, and resilient means cooperating with said diaphragm for biasing said valve member toward open position but only operable to open said valve member when gas pressure develops in said outlet chamber by flow through said bleeder passage if all outlets in communication with said outlet chamber are closed.

35 9. In a safety device for gas appliances, in combination with means providing inlet and outlet chambers and a valve member cooperating with a valve seat for controlling the flow of gas between said chambers, means automatically operative to assure that after closure said valve member remains closed as long as any outlet in communication with said outlet chamber is open, said means including a bleeder passage between said inlet and outlet chambers, said valve member being subjected at its opposite faces to the pressures in said inlet and said outlet chambers, a spring cooperating with said valve member, and 40 means for imposing a tension on said spring to bias the same in opening direction, the tension of said spring being insufficient to open said valve member if the outlet chamber is subjected to atmospheric pressure but operative to move said valve member to open position when gas pressure develops in said outlet chamber by flow through said bleeder passage if all outlets communicating with said outlet chamber are closed, said valve opening means being inoperative to open said valve from the exterior of said device in the absence of said gas pressure in the outlet chamber.

45 10. In a safety device for gas appliances, in combination with means providing inlet and outlet chambers and a valve member cooperating with a valve seat for controlling the flow of gas

between said chambers, means automatically operative to assure that after closure said valve member remains closed as long as any outlet in communication with said outlet chamber is open, said means including a bleeder passage between said inlet and outlet chambers, a diaphragm subjected on its opposite sides respectively to the pressures of said inlet chamber and said outlet chamber, and arms interposed between said diaphragm and said valve member and cooperating with opposed faces of said valve member, said arms being actuated by the flexure of said diaphragm under varying pressure differences at the two sides of said diaphragm for urging said valve member toward open or toward closed position.

11. In a safety device for gas appliances, in combination with means providing inlet and outlet chambers and a valve member cooperating with a valve seat for controlling the flow of gas between said chambers, means automatically operative to assure that after closure said valve member remains closed as long as any outlet in communication with said outlet chamber is open, said means including a bleeder passage between said inlet and outlet chambers, a diaphragm subjected at its opposite sides to the pressure in said inlet and said outlet chambers, resilient means cooperating with said diaphragm, and means actuated by said diaphragm and cooperating with said valve member, said diaphragm being actuated against the tension of said resilient means to urge said valve member toward closed position if said outlet chamber is substantially at atmospheric pressure and said resilient means cooperating with said diaphragm to urge said valve member toward open position if gas pressure develops in said outlet chamber by reason of gas flow through said bleeder passage.

12. In a safety device for gas appliances, in combination with means providing inlet and outlet chambers and a valve member cooperating with a valve seat for controlling the flow of gas between said chambers, means automatically operative to assure that after closure said valve member remains closed as long as any outlet in communication with said outlet chamber is open, said means including a bleeder passage between said inlet and outlet chambers, said valve member being subjected on its opposite sides respectively to the pressures in said inlet and said outlet chambers, and resilient means operable externally of said device and adapted to bias said valve member toward open position and automatic means inoperable from the exterior of said

device for opening said valve member by a decrease in the difference in pressure in said inlet and outlet chambers when gas flow through said bleeder passage develops a pressure in said outlet chamber when all outlets communicating with said outlet chamber are closed.

13. In a safety device for gas appliances, in combination with means providing inlet and outlet chambers and a valve member cooperating with a valve seat for controlling the flow of gas between said chambers, means automatically operative to assure that after closure said valve member remains closed as long as any outlet in communication with said outlet chamber is open, said means including a bleeder passage between said inlet and outlet chambers, pressure operated means subjected on opposite sides respectively to the pressures in said inlet and said outlet chambers, means for actuating said valve member from said pressure operated means, and resilient means biasing said pressure operated means toward open position of said valve member whereby said valve member is held in closed position when said outlet chamber is subjected substantially to atmospheric pressure and said valve member is urged toward open position when gas pressure develops in said outlet chamber by reason of gas flow through said bleeder passage.

14. In a safety device for gas appliances, in combination with means providing inlet and outlet chambers and a valve member cooperating with a valve seat for controlling the flow of gas between said chambers, means automatically operative to assure that after closure said valve member remains closed as long as any outlet in communication with said outlet chamber is open, said means including a bleeder passage between said inlet and outlet chambers, a valve controlling said bleeder passage, a diaphragm subjected on its opposite sides respectively to the pressures in said inlet chamber and said outlet chamber, a spring normally urging said diaphragm in one direction, means for opening the valve in said bleeder passage and biasing said valve member toward open position, and means actuated by said diaphragm and cooperating with said valve member for moving said valve member toward open position only when the pressure on the outlet side of said diaphragm is that developed by reason of gas flow through said bleeder passage when all outlets communicating with said outlet chamber are closed.
